US00D620522S

(12) **United States Design Patent**
Amano

(10) **Patent No.:** US D620,522 S
(45) **Date of Patent:** ** Jul. 27, 2010

(54) **COUPLING FOR TONER CARTRIDGE**

(75) Inventor: **Takafumi Amano**, Kanagawa (JP)

(73) Assignee: **Toshiba Tec Kabushiki Kaisha** (JP)

(**) Term: **14 Years**

(21) Appl. No.: **29/314,692**

(22) Filed: **Apr. 20, 2009**

(30) **Foreign Application Priority Data**

Mar. 3, 2009 (JP) 2009-004695

(51) **LOC (9) Cl.** 16-03

(52) **U.S. Cl.** D18/43

(58) **Field of Classification Search** D14/471; D18/12, 36, 40, 43, 44, 56; 222/DIG. 1; 347/197, 222; 399/24-28, 107-112, 119, 399/121, 122, 222-224

(57) **CLAIM**

The ornamental design for a coupling for toner cartridge, as shown and described.

DESCRIPTION

FIG. 1 is a front perspective view of a coupling for toner cartridge, showing my new design;

FIG. 2 is a rear perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof; and,

FIG. 8 is a left side elevational view thereof.

The broken lines depict environmental subject matter only and form no part of the claimed design.
